Primary Examiner — Cynthia M. Chin*(74) Attorney, Agent, or Firm* — Knobbe, Martens, Olson & Bear, LLP(57) **CLAIM**

The ornamental design for a kart, as shown and described.

DESCRIPTION

FIG. 1 is a front perspective view of a kart, which embodies my design.

FIG. 2 is a front view of the kart of FIG. 1.

FIG. 3 is a rear view of the kart of FIG. 1.

FIG. 4 is a left side view of the kart of FIG. 1.

FIG. 5 is a ride side view of the kart of FIG. 1.

FIG. 6 is a top view of the kart of FIG. 1; and,

FIG. 7 is a bottom view of the kart of FIG. 1.

The broken lines are for the purpose of illustrating portions of the article that form no part of the claimed design.

1 Claim, 5 Drawing Sheets# US D941,397 S
